UNITED STATES PATENT OFFICE.

ANDREW S. NICO, OF LE ROY, NEW YORK, ASSIGNOR TO THE GENESEE PURE FOOD COMPANY, OF LE ROY, NEW YORK, A CORPORATION OF NEW YORK.

SEALED RECEPTACLE.

1,310,289.

Specification of Letters Patent. Patented July 15, 1919.

Application filed July 8, 1916. Serial No. 108,200.

To all whom it may concern:

Be it known that I, ANDREW S. NICO, a citizen of the United States, residing at Le Roy, in the county of Genesee and State of 5 New York, have invented new and useful Improvements in Sealed Receptacles, of which the following is a specification.

My present invention relates to improvements in paper receptacles, and the primary 10 object of the invention is to provide a moisture-proof seal or inclosure for the contents thereof, the invention embodying a novel and improved seal or inclosure which will effectually retain the contents of the receptacle therein and will exclude moisture from 15 the interior of the receptacle. The seal or inclosure, according to the present invention, embodies a plurality of bends which are formed in the paper or material at the 20 mouth of the receptacle, these bends forming sealing corners, and, preferably, means is also provided for locking or retaining the bends in proper form or relation.

To these and other ends, the invention 25 consists in certain improvements, and combinations and arrangements of parts, all as will be hereinafter more fully described, the novel features being pointed out particularly in the claims at the end of the specification.

30 In the accompanying drawing:—

Figure 1 is a perspective view of a paper receptacle constructed in accordance with one embodiment of the present invention.

Fig. 2 represents a section taken transversely through the seal and on the line 2—2 of Fig. 1.

Fig. 3 represents a section, on an enlarged scale, taken longitudinally through a portion of the seal and on the line 3—3 of Fig. 1.

40 Fig. 4 is a perspective view of the upper portion of a sealed receptacle showing another embodiment of the present invention.

Fig. 5 represents a transverse section through the seal shown in Fig. 4, and

45 Fig. 6 represents a transverse section taken through the receptacle and its seal and also through the carton in which the receptacle is packed for shipment.

Similar parts are designated by the same 50 reference characters in the several views.

While the present invention is applicable to receptacles of various types where it is desirable or necessary to seal or protect the contents from moisture and to retain the 55 contents within the receptacle, it is particu-

larly applicable to receptacles made in the form of a bag and composed of moisture-proof paper or similar material which is folded in a manner to provide a suitable space for the contents and to bring all of the 60 free edges of the paper or material together, the margins of the paper or material being then formed so as to seal the contents from moisture and to retain the contents within the receptacle, means being also preferably 65 provided for retaining the margins of the paper or material in sealing relation. A receptacle of this general type is shown and described fully in Letters Patent, No. 1,101,430, granted June 23, 1914, to Otis E. 70 Glidden and myself. The receptacle shown in the present instance is of the same type as that shown and described in said patent, but the present invention provides a sealed closure which differs structurally from that 75 shown in said patent and which possesses certain advantages thereover. The preferred forms of closures or seals are shown in the accompanying drawing and will be herein-after described in detail, but it is to be understood 80 that equivalent constructions are contemplated and will be included within the scope of the claims.

In the present instance, 1 designates the body of the bag or receptacle, it being made 85 up from a blank in the manner shown and described in said prior patent, whereby the margins of the blank are all brought together at the mouth of the bag or receptacle. The receptacle or bag may be made 90 of paper or any other suitable material, but it is preferably made of a paper which is impervious to moisture, a paper coated or treated with paraffin or a so-called "waxed" paper being preferable. Furthermore, in 95 order to facilitate handling of paper of this character in the machines which make up the receptacles, it is preferable to employ a paper which is waxed on the side only which is in the receptacle when the same 100 is made up, and when the margins of the blank are all brought together at the mouth of the receptacle, these waxed surfaces will engage or face one another.

The contents of the bag or receptacle are 105 introduced therein after the bag has been made but before the margins at the mouth of the bag or receptacle have been sealed. After the contents have been introduced into the receptacle, the seal is made, in both em- 110

bodiments of the invention, by bending the margins of the paper or material at the mouth of the bag sharply along the line 2. This sharp bending or creasing causes the 5 lapped or engaged margins of the blank forming the receptacle to stand at an angle, preferably about a right angle, to the vertical dimension of the receptacle. A relatively firm compression is also preferably 10 exerted upon the corner or bend 2, and this compression, in conjunction with the relatively sharp bend, causes the engaging and wax-covered surfaces to conform precisely to one another and to form a seal which 15 will exclude moisture from the receptacle and will prevent leakage of the contents, especially where the contents are in the form of a powder.

The portions 3 of the margin of the 20 blank which extend laterally from the bend 2 and in a plane substantially at a right angle to the vertical dimension of the bag or receptacle lie in close relation to one another, and their free portion 4 is then 25 bent downwardly along the line 5, the bend being preferably at substantially a right angle so that the portion 4 will project downwardly in a plane in substantially right angular relation to the laterally extending 30 portion 3. The bend 5, which is also relatively sharp, is also preferably subjected to compression which will cause the waxed surfaces of the lapped margins of the blank to conform precisely to one another and to 35 form an air-tight seal. By bending the free portion 4 of the margins downwardly at substantially a right angle to the plane of the laterally extending portion 3, relative movement of the lapped portions 3 in 40 planes parallel to one another is prevented, and hence any tendency for the mouth of the bag or receptacle to open, particularly under the pressure of the contents thereof when the receptacle is inverted during han- 45 dling or shipment, is effectually resisted. The bend 5 also coöperates with the bend 2 to complete a perfect moisture-proof seal.

Suitable means is preferably provided for 50 retaining the layers of the paper compos- ing the downwardly extending portion 4 in engagement and for preventing relative shifting of these layers upon one another which would permit separation of these layers at the bend 5. As shown in Figs. 55 1-3 inclusive, tongues 6, of substantially dovetail form, are punched from the layers of paper or material composing the down- 60 wardly-turned portion 4. Preferably, and as shown, the wider portions of these dove- tail tongues are at the free ends thereof, and the tongues are bent on lines 7 which extend vertically or in a direction transverse to the line of the bend 5. The edges of the tongues coöperate with the edges of 65 the openings formed in the adjacent layers

of paper and thereby form interlocks which effectually prevent relative separation of the layers of paper at the bend 5. These tongues are preferably bent at substantially a right angle to the plane of the down- 70 turned portion 4 and they are preferably directed inwardly or toward the receptacle to protect them and to avoid the presence of projections on the receptacle which might be found objectionable. In order to 75 prevent relative movement of the layers of paper composing the downturned portion 4 in a horizontal direction, or a direction longitudinally of the portion 4, one or more of the tongues 6 may be struck from the 80 portion 4 in a reverse relation from the remaining tongues, the bend of the tongues being in a reverse direction, and the lapping tongues 6 will then act, as will appear from Fig. 3, to prevent relative shifting of the 85 layers of paper in either direction longitudinally of the seal.

In Figs. 4, 5 and 6, tongues 8, which are preferably of substantially dovetail form, are struck from the layers of paper in such 90 a manner that these tongues will assist the bend 5 in preventing relative movement of the layers of paper in the laterally bent portion 3 in a direction that would permit opening of the package, and these tongues also 95 prevent relative separation of the layers of paper in the laterally bent portion 3 or at the bend 5. As shown, these tongues 8 are punched from the transversely bent portion 3, the wider portions of the tongues being at 100 the free ends thereof, and these tongues are bent downwardly along the lines 9 at substantially a right angle to the plane of the laterally bent portion 3 so that the tongues extend downwardly in parallelism with the 105 downturned portion 4, or substantially so, and the tongues occupy a position between the downturned portion 4 and the body of the receptacle. Owing to the shape of these tongues, their free ends being larger than 110 the ends thereof which are attached to the portion 3, the edges of the tongues will co- 115 operate with the edges of the openings from which the tongues of adjacent layers are punched to prevent relative separation of the layers in the laterally bent portion 3, and as these tongues are bent on the lines 9, they will supplement the action of the bend 5 in preventing relative shifting of the layers in the portion 3 which might permit 120 opening of the mouth of the receptacle.

Fig. 6 shows one of the receptacles as it is packed within a carton 10. The laterally bent portion 3 of the seal engages a wall 11 of the carton and it is thereby held in right 125 angular relation to the vertical dimension of the receptacle, and hence inversion of the receptacle will not cause opening of the mouth thereof, notwithstanding the fact that the contents of the receptacle are 130

- brought to bear with some pressure upon the converging walls leading to the mouth of the receptacle and which will tend to spread apart these walls and to open the receptacle.
- 5 Relative shifting of the layers of paper in the laterally bent portion 3 under the same influence will be prevented by the second bend 5 and the locking tongues, as herein-before explained.
- 10 I claim as my invention:—
1. A receptacle having its material at the mouth thereof lapped and bent laterally at a sharp angle to form a sealing corner at said mouth and then bent downwardly at a second sharp angle at a point removed from the bend first mentioned, and means punched from said lapped material and serving as a lock to prevent slipping between the layers of the lapped material.
  - 15 2. A receptacle having its material at the mouth thereof lapped and bent at approximately a right angle to form a relatively sharp sealing corner, a portion of said ma-
- terial extending laterally from said corner, and the material at the free edge of said 25 laterally bent portion being bent at approximately a right angle to form a second relatively sharp corner, and means punched from the lapped material and serving as a lock to prevent slipping of the individual 30 layers of the lapped material.
3. A paper receptacle having its material at the mouth thereof lapped and bent laterally at a sharp angle to form a sealing corner at said mouth, said laterally bent lapped 35 portion being thence bent at a second relatively sharp angle at a point removed from the bend first mentioned, and dovetail tongues punched from said lapped material and serving as locks to prevent relative slipping between the layers of the lapped material.

In testimony whereof I have hereunto set my hand.

ANDREW S. NICO.
